Inventor:
John F. Kytlica:
By Chase & Dillman
Atty.

UNITED STATES PATENT OFFICE.

JOHN F. KYTLICA, OF CHICAGO, ILLINOIS.

ROCKER ARM.

Application filed February 12, 1923. Serial No. 618,508.

To all whom it may concern:

Be it known that I, JOHN F. KYTLICA, a citizen of the United States, residing at Chicago, in the county of Cook and State of Illinois, have invented certain new and useful Improvements in Rocker Arms, of which the following is a specification.

This invention relates to improvements in rocker arms in general, but particularly to that type of such arms employed in the operating mechanism for the valves of engines, and it consists in certain peculiarities of the construction, novel arrangement and combination of the parts thereof as will be hereinafter more fully set forth and specifically claimed.

The principal object of the invention, is the provision of a very simple and inexpensive, yet highly efficient rocker arm, which while being shown in the accompanying drawing in connection with a portion of an engine and valve operating mechanism thereof, and will be hereinafter so referred to, yet it is applicable for use for other purposes without departure from the spirit of the invention, and for this reason I wish it to be understood the invention is not limited in its application to any specific use or purpose except where so specified in the claims hereto attached.

Another object of the invention is the provision of means whereby the rocker arm will be so mounted or pivoted that friction incident to its bearings, will be greatly reduced or practically eliminated, and the actuation of the arm rendered extremely sensitive.

Still another object is to so construct certain bearing parts of the arm that after becoming worn from usage, they can be readily ground or put in substantially their original condition with a minimum amount of labor.

A still further object is the provision of means for yieldingly, automatically and accurately holding the arm on its pivot or bearing.

In the accompanying drawing, which serves to illustrate an embodiment of the invention—

Fig. 1 is a plan view of a pair of rocker arms constructed and mounted according to my invention.

Fig. 2 is a side view thereof showing a fragment of the upper portion of the engine 55 on which the rocker arms are mounted, and

Fig. 3 is a view partly in section and partly in elevation, taken on line 3—3 of Fig. 2 looking in the direction indicated by the arrows showing the bearing elements 60 or portions of one of the rocker arms and a part of the supporting base thereof.

Like numerals of reference refer to corresponding parts throughout the different views of the drawings.

The supporting base for the rocker arms is designated by the numeral 5, and as is clearly shown in Fig. 2, is secured by means of bolts 6 and nuts 7 to the upper portion of an engine 8, which engine may be of any 70 well known type having the valves thereof located on its opposite sides.

The supporting base 5 has an upright portion 9 from each side of which, is horizontally extended a V-shaped bearing or pivot 75 member 10 on which one of the rocker arms 11 is mounted for oscillation. As the arms 11 and their bearing or pivot members are of the same construction, a description of one of each of them will be sufficient for a 80 clear understanding of the device. As shown in Figs. 1 and 2, the rocker arm 11 has at one of its ends an arcuate shoe 12 and at its other end an enlargement 13 which is provided in its lower surface with a 85 socket 14 for the reception and operation of the upper end of one of the rods 15 of the valve operating mechanism, not shown, which mechanism may be of the well known or any preferred construction.

The other of the rods 15 impinges at its upper end against the arcuate shoe 12 in the ordinary manner of such rods. The arm 11 is provided midway between its ends with a transverse opening 16 which is substantially circular but has in its lower portion an angular recess 17 to receive the acute angled lower portion of the pivot or bearing member 10 of the support for the arm. To give greater stability to the arm the 100 same is provided on each of its sides around the opening 16 therein with a cylindrical collar or boss 18 each of which has an angular recess 17 coinciding with or forming a part of the angular recess above mentioned, 105 of the arm.

Extended upwardly from the bosses or collars 18 is an internally screw-threaded extension 19 which communicates with the cavities of the portions 18 of the arm and is 5 diametrically intersected by the arm 11 as is clearly shown in Fig. 1 of the drawing.

Movably located in the extension 19 is a follower or plunger 20 which has its upper portion circular in shape to fit snugly in the 10 extension 19 yet so as to move therein, and its lower portion substantially V or wedge-shaped so as to fit in the angular recess 21 of the V-shaped pivot or bearing member 10 as will be readily understood by reference to Fig. 2 of the drawing. This movable follower or plunger carries at its upper end a stem 22 which is loosely extended through an opening in a screw-plug 23 which is in threaded engagement with the extension 19 20 and is employed for adjusting the tension of a spring 24 which surrounds the stem 22 and rests at one of its ends against the inner end of the plug 23 and at its other end against the upper surface of the plunger 25 20, said plunger being preferably provided with a socket 25 in its upper surface for the reception of the lower end of said spring. The plug 23 is provided with openings 26 for engagement with a spanner wrench used 30 for turning the plug 23 in the proper direction to regulate the tension of the spring 24 and through it the pressure of the plunger 20 on the bearing pivot 10 for the rocker arm.

35 By reference to Fig. 2 it will be seen that the lower portion of the V-shaped member 10 is somewhat enlarged as at 10^a and that the lower portion of the angular part of the follower 20 is likewise laterally enlarged 40 as at 20^a for the purpose of enabling the pointed or knife-like edges of the members 10 and 20, after becoming blunted by usage, being ground without the necessity of grinding the entire side walls of said members, 45 thus saving considerable time and labor. The outer end of the lower portion of the enlarged part 10^a of the pivot or bearing member 10 is provided with a vertical opening for the reception of a cotter-pin 27 used 50 for preventing the accidental lateral dislocation of the rocker arm.

From the foregoing and by reference to the drawing, it will be readily understood and clearly seen that by my improvements 55 the angular recess 17 of the rocker arm will receive the knife-like edge of the pivot or bearing member 10 for the arm and that as the follower 20 fits at its knife-like edge into the angular recess 21 of the member 10 and 60 is yieldingly held in such position by the tension of the spring 24 exerted upon the upper portion of the follower 20, a very sensitive and almost frictionless bearing will be provided, and also one in which the pres-

sure of the said follower against the said 65 pivot member can be regulated so as to compensate for the wear of the parts incident to usage.

Having thus fully described my invention, what I claim as new and desire to secure 70 by Letters Patent is:—

1. In a device of the class described, the combination with a V-shaped supporting member, of a rocker arm having a transversely disposed opening surrounding said 75 member and having the wall thereof in contact with the apex of said member, and means carried by the arm and extended into the recess of said supporting member for holding the arm in contact with said member.

2. In a device of the class described, the combination with a V-shaped supporting member, of a rocker arm having a transversely disposed opening surrounding said 85 member and having the wall thereof in contact with the apex of said member, and means carried by the arm and extended into the recess of said supporting member for yieldingly holding the arm in contact with 90 said member.

3. In a device of the class described, the combination with a V-shaped supporting member, of a rocker arm having a transversely disposed opening surrounding said 95 member and the wall of said opening having a V-shaped recess to receive the apex of said supporting member, and means carried by the arm and extended into the recess of said supporting member for holding the arm 100 in contact with said member.

4. In a device of the class described, the combination with a V-shaped supporting member, of a rocker arm having a transversely disposed opening surrounding said 105 member and the wall of said opening having a V-shaped recess to receive the apex of said supporting member, and means carried by the arm and extended into the recess of said supporting member for yieldingly holding the arm in contact with said member.

5. In a device of the class described, the combination with a V-shaped supporting member, of a rocker arm having a transversely disposed opening surrounding said 115 member and having the wall of said opening in contact with the apex of said member, a tubular extension mounted on the arm in communication with the said transverse opening, a follower movably located in said extension and having a V-shaped portion extended into the recess of said member, a spring mounted on the follower within said extension and adjustable means engaging said extension for adjusting the tension of 120 125 said spring.

JOHN F. KYTLICA.
